UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

MULTICOLOR WEB-PERFECTING PRINTING PRESS.

Application filed October 5, 1922. Serial No. 592,577.

To all whom it may concern:

Be it known that I, HOWARD M. BARBER, a citizen of the United States, and resident of Stonington, in the county of New London and State of Connecticut, have invented a new and useful Improvement in Multicolor Web-Perfecting Printing Presses, of which the following is a specification.

In high speed multi-color web perfecting printing presses in common use, the web is passed through numerous couples for the printing of the several colors, thus requiring a press occupying considerable space, requiring a long travel for the web between printings, entailing a loss of register and causing an undue waste of paper when restarting the press after a stoppage for any cause.

My invention comprises a multi-color web perfecting printing press in which all of the colors for one side of the web are printed by the coaction of several form cylinders with a common impression cylinder and all of the colors for the other side of the web are printed by the coaction of several form cylinders with their common impression cylinder, the two printing mechanisms being located in proximity to each other.

My invention also includes a folding mechanism located above the two printing mechanisms and a mechanism for cutting sheets from the web located at one side of the printing mechanisms, whereby the travel of the web is materially reduced, better register and less paper waste is ensured, and a great saving of space is obtained with the maximum amount of accessibility.

A practical embodiment of my invention is represented in the accompanying drawings, in which—

40 Fig. 1 represents an outside view of the press showing more particularly the geared connection between the printing and folding mechanisms.

45 Fig. 2 represents a longitudinal vertical section through the press taken in the plane of the line II—II of Fig. 3.

Fig. 3 represents a transverse vertical section through the press taken in the plane of the line III—III of Fig. 2.

50 The sides of the main frame are denoted by 1 and 2.

Two multi-color printing mechanisms are carried by the main frame, one printing mechanism comprising the plurality of form

cylinders 3 and their common impression 55 cylinder 4, and the other printing mechanism comprising the plurality of form cylinders 5 and their common impression cylinder 6. These form cylinders 3 and 5 are arranged along the outer sides of their respective impression cylinders 4 and 6, rendering the said form and impression cylinders readily accessible. Groups of inking mechanisms 7 and 8, which may be of the well known or approved form, are provided 60 for supplying inks of various colors to their respective form cylinders.

In the present instance the web is led around rollers 9 and 10 to the impression cylinder 4 where it passes around the impression cylinder beneath the form cylinders 3. The web is then led from the impression cylinder 4 around the pulley 11 to the impression cylinder 6 of the second inking mechanism where the other side of the web 75 will be acted upon by the group of form cylinders 5.

An auxiliary frame 12 is mounted on the main frame above the space between the printing mechanisms, which auxiliary frame carries the web folding mechanism, which folding mechanism is herein shown as arranged to impart one longitudinal fold to the web. The web as it passes from the impression cylinder 6 of the second multi-color printing mechanism, is shown as passing around a roller 13 from whence it is led upwardly and around a roller 14. From thence the web is led downwardly over the double folding blade 15 between the coacting 85 rollers 16, 17. From thence the web is led downwardly around the roller 18 and laterally to and over the roller 19, carried by the main frame.

An auxiliary frame 20 is secured to the 95 main frame at one side of the space between the two printing mechanisms, which auxiliary frame carries the mechanism for cutting sheets from the web, arranged at right angles to the said printing mechanisms. 100

The web after it leaves the roller 19 is led laterally and downwardly between the coacting rollers 21, 22 and then downwardly between the coacting rotary cutters 23, 24. From thence the sheets are taken under control by the delivery means 25.

A common drive for the printing, folding and cutting mechanisms is as follows:—

The main drive shaft 26 is provided exterior to the side frame 2 with a gear 27 driven from any suitable source of power, not shown herein.

- 5 This shaft 26 is provided with a gear 28 which meshes with a gear 29, which in turn meshes with the gear 30 of the impression cylinder 4 of the first multi-color printing mechanism. This gear 28 also meshes with 10 the gear 31 of the impression cylinder 6 of the second multi-color printing mechanism. The gears 32 of the form cylinders 3 of the first multi-color printing mechanism are driven from the gear 30 and the gears 33 of 15 the form cylinders 5 of the second printing mechanism are driven from the gear 31. A gear 34 which meshes with the gear 31 also meshes with the gear 35 on the shaft 36, which has a bevel gear driving connection 20 37, 38, with the shaft of the roller 18. This gear 35 in turn meshes with the gear 39 of the shaft 40, which has bevel gear connections 41, 42, 43, 44, with the shafts of the rollers 16 and 17 of the folding mechanisms. 25 The web feeding roller 14 is driven from the gear 39 through the train of gears 45, 46, 47.

The cutting mechanism is driven from the main drive shaft 26 by providing the shaft 26 with a bevel gear connection 48, 49 with the cross shaft 50 of the cutting mechanism, which cross shaft 50 is provided with a gear 51, which drives the rotary cutters through the train of gears 52, 53, 54 of the 30 web feed rollers 21 and 22 through the train of gears 55, 56, 57. The sheet delivery is driven from the gear 52 through the train of gears 58, 59, 60, 61, 62.

By the arrangement of the several mechanisms as herein shown and described, it will be seen that I have provided a minimum travel of the web, thereby obtaining better register and reducing paper waste. It will also be seen that I have been enabled to obtain a material saving in space occupied, and at the same time keeping the parts in readily accessible positions.

It is evident that various changes may be resorted to in the construction, form and arrangement of the several parts without departing from the spirit and scope of my invention, hence I do not wish to limit myself to the particular embodiment herein shown and described, but

55 What I claim is—

1. In a multi-color web perfecting printing press, two proximate multi-color printing mechanisms, each comprising a plurality of form cylinders and a common impression cylinder, a web folding mechanism located above the two printing mechanisms, and means for leading the web through the printing and folding mechanisms.
- 60 2. In a multi-color web perfecting printing press, two proximate multi-color printing mechanisms, each comprising a plurality of form cylinders and a common impression cylinder, a web folding mechanism located above the two printing mechanisms, and means for leading the web through the printing and folding mechanisms.
- 65 3. In a multi-color web perfecting printing press, two proximate multi-color printing mechanisms, each comprising a plurality of form cylinders and a common impression cylinder, a web folding mechanism located above the two printing mechanisms, and means for leading the web through the printing and folding mechanisms.

ing mechanisms, each comprising a plurality of form cylinders and a common impression cylinder, a web folding mechanism located above the two printing mechanisms, means for leading the web through the printing and folding mechanisms, and a common drive for the printing and folding mechanisms.

3. In a multi-color web perfecting printing press, two proximate multi-color printing mechanisms, each comprising a plurality of form cylinders and a common impression cylinder, the form cylinders being arranged around the outer sides of the impression cylinders, a web folding mechanism located above the two printing mechanisms, and means for leading the web through the printing and folding mechanisms.

4. In a multi-color web perfecting printing press, two proximate multi-color printing mechanisms, each comprising a plurality of form cylinders and a common impression cylinder, the form cylinders being arranged around the outer sides of the impression cylinders, a web folding mechanism located above the two printing mechanisms, means for leading the web through the printing and folding mechanisms, and a common drive for the printing and folding mechanisms.

5. In a multi-color web perfecting printing press, two proximate multi-color printing mechanisms, each comprising a plurality of form cylinders and a common impression cylinder, a web folding mechanism located above the space between the two printing mechanisms, and means for leading the web through the printing and folding mechanisms.

6. In a multi-color web perfecting printing press, two proximate multi-color printing mechanisms, each comprising a plurality of form cylinders and a common impression cylinder, a web folding mechanism located above the space between the two printing mechanisms, means for leading the web through the printing and folding mechanisms, and a common drive for the printing and folding mechanisms.

7. In a multi-color web perfecting printing press, two proximate multi-color printing mechanisms, each comprising a plurality of form cylinders and a common impression cylinder, the form cylinders being arranged around the outer sides of the impression cylinders, a web folding mechanism located above the space between the two printing mechanisms, and means for leading the web through the printing and folding mechanisms.

8. In a multi-color web perfecting printing press, two proximate multi-color printing mechanisms, each comprising a plurality of form cylinders and a common impression cylinder, the form cylinders being arranged

around the outer sides of the impression cylinders, a web folding mechanism located above the space between the two printing mechanisms, means for leading the web through the printing and folding mechanisms, and a common drive for the printing and folding mechanisms.

9. In a multi-color web perfecting printing press, two proximate multi-color printing mechanisms, each comprising a plurality of form cylinders and a common impression cylinder, web folding and cutting mechanisms located respectively above and at one side of the two printing mechanisms, and means for leading the web through the printing, folding and cutting mechanisms.

10. In a multi-color web perfecting printing press, two proximate multi-color printing mechanisms, each comprising a plurality of form cylinders and a common impression cylinder, web folding and cutting mechanisms located respectively above and at one side of the two printing mechanisms, means for leading the web through the printing, folding and cutting mechanisms, and a common drive for the printing, folding and cutting mechanisms.

11. In a multi-color web perfecting printing press, two proximate multi-color printing mechanisms, each comprising a plurality of form cylinders and a common impression cylinder, the form cylinders being arranged around the outer sides of the impression cylinders, web folding and cutting mechanisms located respectively above and at one side of the two printing mechanisms, and means for leading the web through the printing, folding and cutting mechanisms.

12. In a multi-color web perfecting printing press, two proximate multi-color printing mechanisms, each comprising a plurality of form cylinders and a common impression cylinder, the form cylinders being arranged around the outer sides of the impression cylinders, web folding and cutting mechanisms located respectively above and at one side of the two printing mechanisms, means for leading the web through the printing, folding and cutting mechanisms, and a common drive for the printing, folding and cutting mechanisms.

13. In a multi-color web perfecting printing press, two proximate multi-color printing mechanisms, each comprising a plurality of form cylinders and a common impression cylinder, web folding and cutting mechanisms located respectively above and at one side of the space between the two printing mechanisms, and means for leading the web through the printing, folding and cutting mechanisms.

14. In a multi-color web perfecting printing press, two proximate multi-color printing mechanisms, each comprising a plurality of form cylinders and a common impression

cylinder, web folding and cutting mechanisms located respectively above and at one side of the space between the two printing mechanisms, means for leading the web through the printing, folding and cutting mechanisms, and a common drive for the printing, folding and cutting mechanisms.

15. In a multi-color web perfecting printing press, two proximate multi-color printing mechanisms, each comprising a plurality of form cylinders and a common impression cylinder, the form cylinders being arranged around the outer sides of the impression cylinders, web folding and cutting mechanisms located respectively above and at one side of the space between the two printing mechanisms, and means for leading the web through the printing, folding and cutting mechanisms.

16. In a multi-color web perfecting printing press, two proximate multi-color printing mechanisms, each comprising a plurality of form cylinders and a common impression cylinder, the form cylinders being arranged around the outer sides of the impression cylinders, web folding and cutting mechanisms located respectively above and at one side of the space between the two printing mechanisms, means for leading the web through the printing, folding and cutting mechanisms, and a common drive for the printing, folding and cutting mechanisms.

17. In a multi-color web perfecting printing press, a main frame, two proximate multi-color printing mechanisms carried thereby, each comprising a plurality of form cylinders and a common impression cylinder, an auxiliary frame surmounting the main frame above the two printing mechanisms, a web folding mechanism carried by the auxiliary frame, and means for leading the web through the printing and folding mechanisms.

18. In a multi-color web perfecting printing press, a main frame, two proximate multi-color printing mechanisms carried thereby, each comprising a plurality of form cylinders and a common impression cylinder, an auxiliary frame surmounting the main frame above the two printing mechanisms, a web folding mechanism carried by the auxiliary frame, means for leading the web through the printing and folding mechanisms, and a common drive for the printing and folding mechanisms.

19. In a multi-color web perfecting printing press, a main frame, two proximate multi-color printing mechanisms carried thereby, each comprising a plurality of form cylinders and a common impression cylinder, the form cylinders being arranged around the outer sides of the impression cylinders, an auxiliary frame surmounting the main frame above the two printing mechanisms, a web folding mechanism carried by the aux-

iliary frame, and means for leading the web through the printing and folding mechanisms.

20. In a multi-color web perfecting printing press, a main frame, two proximate multi-color printing mechanisms carried thereby, each comprising a plurality of form cylinders and a common impression cylinder, the form cylinders being arranged around the outer sides of the impression cylinders, an auxiliary frame surmounting the main frame above the two printing mechanisms, a web folding mechanism carried by the auxiliary frame, means for leading the web through the printing and folding mechanisms, and a common drive for the printing and folding mechanisms.
- 10 21. In a multi-color web perfecting printing press, a main frame, two proximate multi-color printing mechanisms carried thereby, each comprising a plurality of form cylinders and a common impression cylinder, auxiliary frames located above and at one side of the main frame, folding and cutting mechanisms carried by said auxiliary frames, and means for leading the web through the printing, folding and cutting mechanisms.
- 20 22. In a multi-color web perfecting printing press, a main frame, two proximate multi-color printing mechanisms carried thereby, each comprising a plurality of form cylinders and a common impression cylinder, auxiliary frames located above and at one side of the main frame, folding and cutting mechanisms carried by said auxiliary frames, means for leading the web through the printing, folding and cutting mechanisms, and a common drive for the printing, folding and cutting mechanisms.
- 30 23. In a multi-color web perfecting printing press, a main frame, two proximate multi-color printing mechanisms carried thereby, each comprising a plurality of form cylinders and a common impression cylinder, the form cylinders being arranged around the outer sides of the impression cylinders, auxiliary frames located above and at one side of the main frame, folding and cutting mechanisms carried by said auxiliary frames,
- 40 24. In a multi-color web perfecting printing press, a main frame, two proximate multi-color printing mechanisms carried thereby, each comprising a plurality of form cylinders and a common impression cylinder, the form cylinders being arranged around the outer sides of the impression cylinders, auxiliary frames located above and at one side of the main frame, folding and cutting mechanisms carried by said auxiliary frames, means for leading the web through the printing, folding and cutting mechanisms, and a common drive for the printing, folding and cutting mechanisms.
- 45 25. In a multi-color web perfecting printing press, two proximate printing mechanisms, each comprising a plurality of form cylinders and a common impression cylinder, a folding mechanism located above the printing mechanisms, a cutting mechanism located at the side of the printing mechanisms and at right angles thereto, means for leading the web through the several mechanisms, the web passing longitudinally between the printing mechanisms vertically to the folding mechanism and laterally to the cutting mechanism.
- 50 26. In a multi-color web perfecting printing press, two proximate printing mechanisms, each comprising a plurality of form cylinders and a common impression cylinder, the form cylinders being arranged around the outer sides of the impression cylinders, a folding mechanism located above the printing mechanisms, a cutting mechanism located at the side of the printing mechanisms and at right angles thereto, means for leading the web through the several mechanisms, the web passing longitudinally between the printing mechanisms vertically to the folding mechanism and laterally to the cutting mechanism.

and means for leading the web through the printing, folding and cutting mechanisms.

55 24. In a multi-color web perfecting printing press, a main frame, two proximate multi-color printing mechanisms carried thereby, each comprising a plurality of form cylinders and a common impression cylinder, the form cylinders being arranged around the outer sides of the impression cylinders, auxiliary frames located above and at one side of the main frame, folding and cutting mechanisms carried by said auxiliary frames, means for leading the web through the printing, folding and cutting mechanisms, and a common drive for the printing, folding and cutting mechanisms.

60 25. In a multi-color web perfecting printing press, two proximate printing mechanisms, each comprising a plurality of form cylinders and a common impression cylinder, a folding mechanism located above the printing mechanisms, a cutting mechanism located at the side of the printing mechanisms and at right angles thereto, means for leading the web through the several mechanisms, the web passing longitudinally between the printing mechanisms vertically to the folding mechanism and laterally to the cutting mechanism.

65 26. In a multi-color web perfecting printing press, two proximate printing mechanisms, each comprising a plurality of form cylinders and a common impression cylinder, the form cylinders being arranged around the outer sides of the impression cylinders, a folding mechanism located above the printing mechanisms, a cutting mechanism located at the side of the printing mechanisms and at right angles thereto, means for leading the web through the several mechanisms, the web passing longitudinally between the printing mechanisms vertically to the folding mechanism and laterally to the cutting mechanism.

70 In testimony, that I claim the foregoing as my invention, I have signed my name this 95 third day of October A. D. 1922.

HOWARD M. BARBER.
